UNITED STATES PATENT OFFICE.

ERNEST W. CURTIS, OF SELBY, CALIFORNIA.

COPYHOLDER.

Application filed April 7, 1922. Serial No. 550,373.

To all whom it may concern:

Be it known that I, ERNEST W. CURTIS, a citizen of the United States, residing at Selby, in the county of Contra Costa and State of California, have invented new and useful Improvements in Copyholders, of which the following is a specification.

This invention relates to improvements in copyholders.

10 The principal object of this invention is to produce a copyholder which may be used in conjunction with a typewriter, linotype machine or in any other form for holding work which a person is to transcribe, or 15 set up.

Another object is to produce a device of this character which may be easily adjusted to engage the standard framework of any typewriter or support.

20 Another object is to produce a simple device of this character which will be cheap to manufacture and consequently well within the means of any person.

Another object is to produce a copyholder 25 which is compact and which when employed will expose but a single line of the copy and at the same time prevent confusion.

Other objects and advantages will be apparent during the course of the following 30 description.

In the accompanying drawings forming a part of this specification, and in which like numerals are employed to designate like parts throughout the same.

35 Fig. 1 is a front elevation of a standard typewriter having my device applied thereto,

Fig. 2 is a top plan view of my device taken on the line 2—2 of Figure 1 and showing the frame in cross section,

40 Fig. 3 is an end elevation of my device, Fig. 4 is a cross section taken on the line 4—4 of Figure 2,

Fig. 5 is a cross section taken on the line 5—5 of Figure 2,

45 Fig. 6 is a detail perspective view of the rolling element, and

Fig. 7 is a diagrammatic view showing the manner in which the copy is wound from the roll.

50 In the accompanying drawings wherein for the purpose of illustration is shown a preferred embodiment of my invention, the numerals 8 and 9 refer to the usual angular vertical supports of a typewriter. At 11 I

have shown a substantially tubular casing 55 which is provided with off set portions as shown at 12 and 13. These offset portions are adapted to receive the ends of clamps. These clamp ends being shown at 14 and 16, while the numerals 17 and 18 refer to enlarged portions each provided with a lug as shown at 19 and 21. An arm 22 is formed upon each of these clamps and carries a set screw as shown at 23 and 24 which set screw in turn contacts the vertical members 65 8 and 9. Mounted within the substantially tubular member 11 and at both ends thereof are resilient supports indicated as a whole by the numerals 26 and 27. These clamping members may be made in any convenient 70 form and are here shown as comprising two resilient arms 28 and 29 which are spread at their free ends so as to retain the rolling element therebetween. This rolling element consists of the tubular member 31 having a 75 slot 32 formed in substantially the entire length thereof. Collars 33 and 34 are provided at one end and are adapted to lie on opposite sides of the resilient support 27. A knurled knob 36, is secured to one end of 80 the rolling element and provides means for rotating the same.

The operation of my device is as follows:—

The matter to be copied is preferably 85 written upon a roll of paper as shown at A, Figures 5 and 7. The free end is now inserted in the slot 32 and the rolled paper dropped into the substantially tubular member 11 and between the resilient supports 90 26 and 27. The rolling element with the free end of the paper attached thereto is now inserted in the resilient supports as best shown in Figures 1 and 2 and as the same is rotated the paper will be unrolled 95 from the roll and wound upon the rolling element. A guide 37 may be provided which comprises a resilient strip secured to the interior of the cylindrical member and adapted to have its free end contact the paper, being wound upon the rolling element. It will thus be seen that I have provided a very simple means whereby a person such as a stenographer may make her notes upon a roll of paper and by properly coiling the same it may be mounted upon the front of the typewriter and wound off as required. This will greatly assist in the speed, ac-

curacy and will eliminate the fatigue of constantly turning the head in looking to and from the typewriter to the notes.

It is to be understood that the form of my invention herewith shown and described, is to be taken as a preferred example of the same, and that various changes in the shape, size and arrangement of parts may be resorted to without departing from the spirit of the invention or the scope of the subjoined claims.

Having thus described my invention, I claim:—

1. In a copyholder, the combination, of a substantially tubular member adjustable clamps mounted on said tubular member, resilient supports mounted within said member and at points adjacent the ends

thereof and a rolling element demountably supported in said resilient supports, substantially as and for the purpose described.

2. In a copyholder, the combination of a substantially tubular member, adjustable clamps mounted on said tubular member, resilient supports mounted within said tubular member and at points adjacent the ends thereof and a rolling element movably supported in said resilient supports, said rolling element comprising a tubular member having a slot formed substantially the length thereof, collars formed on said tubular member and adapted to prevent endwise movement thereof and means for rotating said rolling element.

In testimony whereof I affix my signature.

ERNEST W. CURTIS.
